METHOD OF PRODUCING FINISHED
FABRICClarence T. Graham, North Attleboro, Mass., as-
signor to William H. Bannon, Mansfield, Mass.

Application August 29, 1938, Serial No. 227,436

10 Claims.

(Cl. 8—115)

This invention relates to the method of producing a new type of finished fabric.

For some time past the textile weaving mills have produced a fabric, such as marquisette, that is relatively thin and is of an open weave. This fabric carries pile that consists either of rovings or of yarn, the pile being interengaged with threads of the ground fabric. Sometimes these rovings or yarn are sheared long and sometimes short. Sometimes they are formed into spaced dots arranged on the obverse side of the fabric ground. At other times they are otherwise arranged and are of such configuration as to form various designs. An example of such a fabric is what is commonly known on the market as a fluff dot marquisette.

Since the beginning of the manufacture of this fabric the finishing of the fabric has been somewhat of a problem. It is desirable, of course, at times to dye the fabric, at other times to bleach it, and to stiffen the ground fabric, which has either been bleached or dyed or is yet in the gray. The problem of stiffening the ground fabric has revolved around the possibility of so stiffening without destroying or changing the condition of the rovings or yarns that form the pile or the fluff dots. These rovings or yarns, forming the pile of the various configurations, have in the past sometimes been fluffed up after they have been sheared and at other times have been permitted to remain in the condition that existed after the shearing, or bleaching.

Heretofore the stiffening of the ground of this type of fabric has been purely a mechanical one, that is to say, in the past the ground fabric has been starched and the penetration of the starch into the fabric arrested before it reached the pile, thus permitting the pile to remain in its soft condition. The disadvantage here of course is that when it is necessary to launder the fabric the water removes the starch from the fabric and leaves it in a raggy condition. If the fabric is to be restarched at home or by commercial laundries it has been the practice of dipping the fabric in a starch solution and laundering as ordinarily light fabric is laundered, which, of course, has resulted in the application of starch to the pile, thus destroying the original effect of having a crisp background and a soft fluffy pile.

That is as far as the art has advanced today.

My invention contemplates chemically changing the ground fabric without chemically changing the pile or affecting the pile in any way and I contemplate a chemical change which will impart to the ground fabric what is commonly

known as a permanent finish, that is to say, to impart a finish to the ground fabric that will permit the laundering of the fabric without destroying the "hand" of the ground and without changing the original soft, or fluffy, condition of the pile or fluff dots.

I contemplate the finishing of this fabric to give the ground a desirable "hand" of permanent finish while maintaining the original condition of the pile, that is, its soft and fluffy condition, by applying a chemical agent or agents to the ground fabric, permitting them to remain in the ground fabric for a sufficient length of time to alter its chemical composition, and removing the agent or agents from the ground fabric or neutralizing them before they affect the pile.

I contemplate other steps as will appear in the following description.

I disclose herein drawings for the purpose of illustrating the manner in which this method may be carried out, in which:

Figures 1 and 1A are diagrammatic views of the various combinations of steps that may be employed;

Figure 2 is a plan view of a fabric formed by my process;

Figure 3 is a section of the fabric before the dots have been fluffed; and

Figure 4 is a similar view after the dots have been fluffed.

The cotton fabric as it comes from the textile mill consists of a ground 1 (Figure 2) of the usual warp and weft, as are found, for instance, in cotton marquisettes. Rovings, yarns or threads 2, are interengaged with the ground threads so that the bight portions 3 of the former are on the reverse side of the ground and the ends are extended from the obverse side of the ground. When this cotton fabric comes from the textile mill to the finishing mill the pile 2 is in the condition shown in Figure 3, generally, so that the problem is to finish the ground or give it a "hand" without finishing the rovings, yarns or threads that form the pattern forming portions of the obverse side of the ground, and without destroying their natural or created fluffiness.

The invention contemplates in one of its stages the finishing of fabric of this nature to retain the pattern or figure forming portions in their original condition, either as they come from the textile mill or after the fabric has been bleached, and also contemplates the imparting of a fluffiness to the rovings or yarns or threads that form the pattern or figure forming portions either before

or after the ground of the fabric has been finished.

The imparting of a permanent finish to a plain cotton textile fabric having no pile is not new. It is shown, for instance, in the Schuttig United States Patent 1,451,306, dated April 10, 1923, and also in the Heberlein United States Patent 1,439,512, dated December 19, 1922.

In my present process I propose to use, among other things, basically what is disclosed in these two United States patents insofar as the permanent finishing of the ground fabric is concerned.

In its most specific detail my process consists of steps 1 to 25 (disclosed in the drawings) inclusive, but some of these steps may be omitted and the steps may be rearranged as will later appear.

In carrying out the process the fabric is moved continuously preferably from the beginning to the end of the process.

The steps disclosed in the drawings are:

1. The application of a "retarder" to the fibers from which the raised pattern or figure forming portions are formed but not to the ground of the fabric.

2. The drying of the fabric.

3. The application of an "accelerator" to the ground but not to the raised pattern or figure forming portions.

4. The drying of the fabric.

5. The application of an acid to the back of the ground fabric.

6. The washing of the acid from the fabric.

7. The drying of the fabric.

8. The application of a "retarder" as in step No. 1.

9. The drying of the fabric.

10. The application of an "accelerator" as in step No. 3.

11. The drying of the fabric.

12. The application of a caustic alkali to the back of the ground fabric.

13. The washing of the alkali from the fabric.

14. The drying of the fabric.

15. The application of a "retarder" as in steps Nos. 1 and 8.

16. The drying of the fabric.

17. The application of an "accelerator" to the fabric as in steps Nos. 3 and 10.

18. The drying of the fabric.

19. The application of an acid to the back of the ground fabric.

20. The washing of the acid from the fabric.

21. The drying of the fabric.

22. The fluffing of the raised pattern or figure forming portions to impart a fluffiness to the same.

23. The moistening of the fabric ground only prior to the placing it in the tenter frame.

24. The passing of the moistened fabric through a drying zone while on the tenter frame.

25. The projecting of a fluid such as steam or air under pressure on to the fabric to impart a final fluffiness to the raised pattern or figure forming portions.

As an alternate of steps 6, 13 and 20, the fabric may be subjected instead of to water, to a neutralizing agent to neutralize the acid and alkali that has been applied to the fabric or, indeed, the fabric may be passed through a water bath to which neutralizing agents have been added.

Definitions

Retarder.—This may be any of many which

include the well known trade-mark retarder such as "Neva-Wet," commercially sold by the Neva-Wet Corporation of America, Inc.; "Impregnole," commercially sold by the Warwick Chemical Company, and other similar compositions may be used.

I also may use a retarder consisting of 50% gum arabic, 48% dextrine and 2% wax.

The purpose of the retarder is to render the raised pattern or figure forming portions less susceptible to penetration of moisture than they would be without the presence of the retarder. In other words, the retarder tends to render the raised pattern or figure forming portions repellent to moisture, or, in other words, less absorbent.

Accelerator.—This may be any of many accelerators, such as are commercially sold under the trade-mark "Tetranol 1638," commercially sold by the Arkansas Co., Inc., "Alkariol," commercially sold by the E. I. Du Pont De Nemours & Co., Inc., or others of the same general character, which fall in the group known as the sulphonated fatty alcohols, or I may use other accelerators, such, for instance, as one made up of approximately forty per cent (40%) pine oil, forty per cent (40%) sulphonated castor oil, and twenty per cent (20%) "Cellosolve," commercially sold by the Carbide & Carbon Chemical Corp.

I may also use an accelerator consisting of ten per cent (10%) triethanolamine, forty per cent (40%) pine oil and fifty per cent (50%) sulphonated castor oil.

The purpose of the accelerator is to render the ground fabric more susceptible to penetration by moisture; that is to say, it hastens the penetration of the moisture beyond that which normally exists if no accelerator were used. The object of the accelerator is directly opposite to that of the retarder.

Acids.—I contemplate using many acids or combinations of acids that would change the character of the cotton forming the ground fabric so that it will be rendered substantially transparent and resilient as distinguished from a dull, transparent or truly parchmentized fabric.

Among these acids are those such as disclosed in the two patents above referred to. For instance, I may use a sulphuric acid of over 50½° Bé (not substantially less than 51° Bé) in the manner and for the reason set forth in the Heberlein Patent 1,439,512, above referred to.

Or I may use an acid such as set forth in the Schuttig Patent 1,451,306, above referred to, and for the reasons and in the manner set forth in the said patent. This acid solution, for instance, is made of nitric acid (100%) 50%, sulphuric acid (100%) 31.6%, water 18.4%.

By the use of either of these acids the effect above outlined on the ground fabric is produced and of course any variations of these concentrations and of the combinations of acids may be possible, but having actually used the acids disclosed in the Heberlein and Schuttig patents above referred to, I know that such acids will convert the cotton fibers of the base of the fabric into a permanent finish, that is, into transparent and resilient fibers as distinguished from dull, translucent or truly parchmentized fibers.

Or I may use mixed acid consisting of 1% nitric (100%) and 99% sulphuric (66%), the mixture being diluted to 56° Bé. When this mixture is used it is permitted to act upon the ground fabric for two seconds at 10° centigrade, but this mixture and times may vary as for instance

by varying the nitric acid between the limits of 5% to 50% and between the limits of 50° Bé to 57.5° Bé. The temperatures may vary from 0° centigrade to 20° centigrade and the time of treatment may vary from 1 to 10 seconds. These combinations, too, will produce a permanent finish as it is now known. When the caustic soda is used, as will later appear, 50° Bé is preferable and its use on the ground fabric for from 5 to 2 minutes at any temperatures is preferable.

Alkali.—Caustic alkali such as caustic soda.

Fabric.—One fabric (A) that I contemplate subjecting to my process to produce the ultimate fabric, is a cotton fabric such as cotton marquisette, which has pattern or figure forming portions raised from and extending from the obverse side of the fabric, which portions are interengaging with the ground threads of the fabric. These raised portions may either be cotton or wool or silk, or any other substance that would normally be susceptible to acid or alkali, and in which the raised pattern or figure portions have not been fluffed or brushed mechanically.

I contemplate using also such a fabric (B) as above described, wherein the raised pattern or figure forming portions have been mechanically fluffed or brushed.

I contemplate treating either of the above fabrics in the gray, that is, prior to their having been bleached.

I contemplate treating either of the above fabrics after they have been bleached as, for instance, with a peroxide bleach.

I contemplate treating either of the above fabrics after they have been mercerized or subjected to the action of a caustic alkali.

Neutralizer.—Any well known neutralizer may be used.

Supposing now that an unbleached and unmercerized fabric of the character of the fabric (A) above, is to be subjected to all of the steps disclosed in the drawings and outlined heretofore in the specification, the fabric is moved continuously, preferably in a direction indicated from right to left in Figure 1 of the drawings so that the raised pattern or figure forming portions 2 are on the upper side of the fabric. The retarder is first applied to the fibers from which the pattern or figure forming portions are made as for instance by passing the fabric first beneath a retarder applicator 4, which is so constructed that it will apply a retarder of a type hereinbefore disclosed to the upper portions only of the pattern or figure forming portions 2 of the fabric. This may be accomplished, for instance, by a wick 5. The fabric is then passed through a dryer of any well known type, such as a hot air dryer 6. The time interval between the application of the retarder and the drying of the fabric in the dryer 6 is such that the penetration of the retarder will be arrested in the raised pattern or figure forming portions, and the retarder will be prevented from penetrating into the ground portion 1 of the fabric.

The fabric then passes on and the ground fabric is subjected to an accelerator of a type hereinbefore disclosed. This is accomplished by having the fabric pass over the periphery of a roller 7 that is submerged in the accelerator of the type described in a tank 8. The fabric then passes on to a similar dryer 9, the time interval between the application of the accelerator to the back of the base fabric and the drying of the fabric in the dryer 9 being such that the accelerator will be permitted to penetrate the base

fabric but will not be permitted to penetrate the raised pattern or figure forming portions. After the drying of the fabric in the dryer 9, the fabric passes on and over and in contact with a roller 10, which is submerged in an acid bath (of any of the acids hereinbefore referred to) in a tank 11. Thus the acid is applied to the back of the fabric and its penetration into the raised pattern or figure forming portions 2 is repelled by the retarder, with the result that the ground fabric is subjected to the action of the acid but the raised pattern or figure forming portions are not.

The entire fabric is then plunged into a water bath in a tank 12, passing around rollers 13 and 14, or it is subjected to a spray washing by a sprayer 15 before the acid reaches the raised or pattern forming portions on the obverse side of the ground. The effect of this is to wash the acid from the fabric and arrest its reaction with the cellulose. Of course this reaction may be arrested also by subjecting the fabric to a neutralizing agent, either with or without the presence of water. The time interval intervening between the application of the acid to the fabric and the neutralizing of the acid or the washing of the acid from the fabric must be such that a chemical reaction will take place between the acid and the cellulose of the fabric ground to such an extent that the chemical character of the outside of the cotton fibers will be altered by the reaction and yet an unaltered core will be retained. If the entire cotton is altered chemically by this reaction the strength and flexibility of the fabric will be destroyed. The strength depends upon the presence of some unaltered cotton and it is for this reason that an unaltered core must be retained. Of course the degree of penetration and of reaction determines the degree of transparency and the time intervening between the application of the acid and the arresting of the reaction is governed somewhat by the desire of the operator and the transparency requirement.

It has been found that, for instance, sulphuric acid at 54° Bé. may be allowed to react with the cotton or cellulose for about five seconds without destroying the strength or the resiliency of the cotton. This is disclosed in the Heberlein patent above referred to. The Schuttig patent above referred to also discloses the rapidity with which the reaction must be arrested when the Schuttig acid is used.

From the washer 12 the fabric passes through a dryer 16 and then again beneath a retarder 17 of the character of the retarder 4 and which operates in a similar manner. It passes then through a dryer 18 which dries the fabric in the manner described in connection with the dryer 6. From the dryer 18 the fabric passes over a roller 19 in a tank 20, which contains an accelerator and which roller 19 acts in the same manner as the roller 7 previously described and for the same purpose. The fabric then passes through a dryer 21, the time interval between the application of the retarder from the supply 17 and the drying of the fabric being substantially the same as that between the application of the retarder from the source 4 and the drying of the fabric in the dryer 6, and the time intervening between the application of the accelerator by the roll 19 and the drying of the fabric in the dryer 21 being substantially the same as that intervening between the applica-

tion of the accelerator by the roll 7 and the drying of the fabric in the dryer 9.

After the fabric leaves the dryer 21 it passes over a roller 22 which is located in a tank 23, which latter contains a caustic alkali. The caustic alkali is applied to the back of the ground 1 of the fabric as the fabric travels over and in contact with the roller 22. The fabric is then washed in a wash tank 24, the fabric passing over rollers 25 and 26 and either being submerged in water contained in the tank or subjected to a spray of water from a spray head 27. Of course the time intervening between the application of the alkali by the roller 22 and the washing of the alkali from the fabric or the arresting of its action upon the fabric being such that the alkali will be permitted to react with the ground fabric but will be prevented from reacting with the raised pattern or figure forming portions. The time interval here of .5 to 2 seconds has been found to be successful.

From the washing operation the fabric then travels through a dryer 28 where it is dried.

After passing through the dryer 28 and being dried, the fabric then passes beneath a retarder applicator 29 which is similar to and operates in a manner similar to the retarders 4 and 17. Here a retarder is applied to the raised pattern or figure forming portions in a manner which has previously been described and then the fabric is passed through a dryer 30 to arrest the travel of the retarder, the time interval between the application of the retarder and the drying of the fabric at this point being substantially the same as that intervening between the application of the retarder by the applicator 4 and the drying of the fabric in the dryer 6.

The fabric then again passes over a roller 31 in a tank 32 containing an accelerator. In this passage the back of the fabric contacts with the periphery of the roller and the accelerator is applied. The fabric then passes through a dryer 33 where the fabric is dried and the action of the accelerator arrested. The time interval here between the application of the accelerator and the drying of the fabric is substantially the same as between the application of the accelerator by the roller 7 and the drying of the fabric in the dryer 9. From the dryer 33 the fabric then passes over a roller 34 in a tank containing any one of the acids or mixtures hereinbefore referred to. As the fabric passes over in contact with the face of this roller 34, the acid is applied to the back of the fabric. The fabric is then subjected to the action of the water in tank 35 passing over the rollers 36 and 37 or to the action of water from a spray head 38, the time intervening between the application of the acid by the roller and the arresting of its action in the tank 12.

The fabric then passes through a dryer 39 where it is dried. Up to this point the fabric has been subjected first to the action of an acid then an alkali, and then an acid, which results, as set forth in the two patents above mentioned, in the chemical change in the cellulose of the fabric ground, imparting to the fabric ground what is known as a permanent finish wherein it is characterized by the fact that the cotton fibers have been altered to be substantially transparent and resilient, as distinguished from a dull, translucent or truly parchmentized fabric. This permanent finish imparts a crispness and resiliency to the fabric and gives it what is known as a "hand." But up to this time the raised pattern or figure

forming portions have been subjected to no chemical reaction so that they retain their original chemical composition and mechanical form. Thus we have a fabric the ground of which has been chemically altered to alter its physical characteristics and the raised pattern or figure forming portions of which have not been chemically altered and retain their original physical characteristics. The fabric may be subjected to any washing operation as any ordinary permanent finished fabric such as permanent organdie or permanent marquisette, both of which and many similar types of fabric may be treated by this method.

Of course it is to be understood that instead of using water in the tanks 12, 24 and 35, neutralizing agents may be used and these may be any well known agents. The acids may be such as I have heretofore described or their equivalents, as may likewise be the alkalis and the retarders and accelerators. It is not necessary that I apply the retarders and accelerators as often as I have heretofore described, for they may be so applied that one application will last through several of the succeeding operations. Thus it is possible to omit the application of the retarder by the applicator 17 for instance, or in some instances it may be possible to omit the application of the retarder by the applicator 17 and the applicator 29. Likewise it may be possible to omit the application of the accelerator by the roller 19 or the application of the accelerator by the rollers 19 and 31. The inclusion or the omission of these steps is dependent upon the lasting qualities of the retarders and accelerators used under the conditions to which they are subjected.

Moreover, instead of applying acid-alkali-acid I may apply alkali-acid-alkali, in which latter case the alkali will be contained in the tank 11, the acid in the tank 23 and the alkali in the tank in which the roller 34 is mounted, the other operations remaining the same. Indeed, I may omit one of the acid steps and apply only acid-alkali, in which instance the tank 35 and its associated parts will be omitted.

Moreover I have found that one acid application alone produces a desirable finish and when using this the second acid step will be omitted. When one acid step alone is used we get a permanent finish which is somewhat duller than the finish I have above described and is somewhat like a linen finish.

After the fabric leaves the dryer 39 it is then subjected to the final finishing operations which consist in subjecting the pattern or figure forming portions to a fluffing action which may either be by mechanical contact or with compressed fluid such as air or steam, or may be a combination of both. In the drawings I have illustrated a preliminary fluffing operation which consists in fluffing the pattern or figure forming portions by means of a rotary brush 40 which engages the pattern or figure forming portions and fluffs them so that their ends extend away from the obverse side of the fabric.

The pattern or figure forming portions may be subjected to a fluffing operation prior to the entry of the fabric beneath the first retarder applicator 4 if this is found desirable.

After the fabric leaves the fluffer 40 it then passes over a roller 41 which operates in a tank 42 containing moisture so that the ground of the fabric alone is moistened. The purpose of this moistening is to permit the fabric to be stretched

into form by the tenter frame 43. After the fabric leaves the moistener 41 it is engaged with the usual tenter frame 43 and is carried along by said frame which moves in the usual manner. This tenter frame passes into a heating zone or chamber 44 and the fabric passes over a platen 45. As the fabric passes over the platen it passes beneath fluid pressure jets 46 which project fluid under pressure on to the obverse side of the fabric. This fluid may be steam, air or any gas, and the purpose of the projection is to further and finally fluff the raised pattern or figure forming portions whether they be in the form of spaced dots or other configurations. From this fluffing operation the fabric passes on to the usual packing operation.

In the above description I have shown how the process in its entirety is applicable to the finishing of unbleached and unmercerized fabric of the (A) class above.

Of course the same steps may be used in connection with the (B) fabric above described.

The same is also true of either the (A) or the (B) fabrics when they have been bleached prior to the carrying on of this process. The bleaching, however, when a bleach such as a peroxide bleach is used, will fluff the pattern or figure forming portions before they are subjected to the instant process as this fluffing is incident to the bleaching.

However, when either the (A) or (B) fabrics have been mercerized prior to being subjected to the instant process it is not necessary to use an acid-alkali-acid treatment, such as has been described because the mercerizing replaces one of these steps and I have found it desirable to use merely an acid-alkali treatment such as described in the Schuttig patent hereinbefore referred to. This in effect gives us an alkali-acid-alkali treatment with the initial alkali treatment taking place as a separate operation.

Of course many subcombinations of this entire combination of steps are possible within the scope of this invention.

The outstanding steps that are essential are the treating of the base fabric to alter the chemical composition thereof without altering the physical appearance of the pattern or figure forming portions that protrude from the obverse side of the ground. The treatment of the ground fabric may vary in many subcombinations of this general process and the ground fabric may have the accelerator applied while at the same time the retarder is applied to the pattern or figure forming portions. On the other hand, the accelerator may be omitted and the retarder applied. Moreover, the retarder may be omitted and the accelerator applied, or both may be omitted. Of course, regardless of the treatment of the ground fabric and the raised pattern or figure forming portions by the entire process or any subcombination thereof, steps 22, 23, 24 and 25 may be either used or omitted depending upon the condition in which it is desired to leave the pattern or figure forming portions.

I have found that a satisfactory fabric is produced by using all of the twenty-five operations hereinbefore described, and this when either the acid disclosed in the Heberlein patent above referred to or the Schuttig patent above referred to is used. I have also found that a satisfactory fabric is produced when the following operations alone are followed (referring to these operations by the numbers attributed to them on the draw-

ings): (1), (2), (3), (4), (5), (6), (7), (8), (9), (10), (11), (12), (13), (14), (22), (23), (24), and (25), and this when either of the two acids above referred to has been used. But, as I have heretofore stated, the process is not to be limited to this combination or subcombination.

The treatment of the ground fabric with the acid disclosed in the Heberlein patent probably results in the conversion of the fibers (except 10 the cores thereof) into a cellulose sulphate, while the treatment with the acid disclosed in the Schuttig patent probably results in the conversion of the cotton fibers (except the cores thereof) into a cellulose nitrate.

15 It is to be understood that the mechanism herein disclosed is only a conventional representation of how the method may be carried out for other mechanisms may be used and indeed the method may be carried out by hand.

20 What I claim is:

1. The method of treating cotton fabric that includes an open mesh ground and spaced groups of yarn or roving fibers engaged with the ground and having free ends extending away from the 25 obverse side of the ground and bight portions engaged with certain of the threads of the ground to produce a fabric having a "permanent finish" ground and "unfinished" groups of fibers on the obverse side of the ground, which includes the 30 steps of: subjecting the ground to successive treatments of acid and alkali capable of producing a permanent relatively transparent and stiff finish, and arresting the actions of said acid and alkali before the character of the free ends of the 35 fibers is affected by rendering said acid and alkali chemically inactive in situ.

2. The method of treating cotton fabric that includes an open mesh ground and spaced groups of yarn or roving fibers engaged with the ground and having free ends extending away from the obverse side of the ground and bight portions engaged with certain of the threads of the ground to produce a fabric having a "permanent finish" ground and "unfinished" groups of fibers on the obverse side of the ground, which includes the 40 steps of: subjecting the ground to the successive treatments of acid and alkali capable of producing a permanent, relatively transparent and stiff finish, and arresting the successive actions of the acid and alkali by neutralization before the acid or alkali affects the free ends of the fibers whereby the original character of said free ends is preserved.

3. The method of treating cotton fabric that 45 includes an open mesh ground and spaced groups of yarn or roving fibers engaged with the ground and having free ends extending away from the obverse side of the ground and bight portions engaged with certain of the threads of the ground to produce a fabric having a "permanent finish" ground and "unfinished" groups of fibers on the obverse side of the ground, which includes the 50 steps of: subjecting the ground to the successive treatments of acid and alkali capable of producing a permanent, relatively transparent and stiff finish, arresting the successive actions of the acid and alkali by neutralization before the acid or alkali affects the free ends of the fibers whereby the original character of said free ends is preserved, and frictionally acting on the free ends of said fibers to produce a fluffy appearance of spaced groups thereof.

4. The method of treating cotton fabric that 55 includes an open mesh ground and spaced groups

of yarn or roving fibers engaged with the ground and having free ends extending away from the obverse side of the ground and bight portions engaged with certain of the threads of the ground to produce a fabric having a "permanent finish" ground and "unfinished" groups of fibers on the obverse side of the ground, which includes the steps of: subjecting the ground to a chemical reaction capable of producing a permanent, relatively transparent and stiff ground and arresting the said chemical reaction before it affects the original character of the free ends of the fibers by rendering the chemical inactive in situ, and fluffing said free ends to form fluffed up and spaced groups of fibers on the obverse side of the ground whereby the free ends of said groups of fibers are "unfinished" and the ground is "permanently finished."

5. The method of treating cotton fabric that includes an open mesh ground and spaced groups of yarn or roving fibers engaged with the ground and having free ends extending away from the obverse side of the ground and bight portions engaged with certain of the threads of the ground to produce a fabric having a "permanent finish" ground and "unfinished" groups of fibers on the obverse side of the ground, which includes the steps of: subjecting the ground to the successive treatments of acid and alkali capable of producing a permanent, relatively transparent and stiff 30

acid and alkali by dilution before the acid or alkali affects the free ends of the fibers whereby the original character of said free ends is preserved.

- 5 6. The method of treating cotton fabric as recited in claim 1 wherein before the ground is subjected to the acid and alkali treatments a retarder is applied to the fibers from which the groups of fibers are formed.
- 10 7. The method of treating cotton fabric as recited in claim 2 wherein before the ground is subjected to the acid and alkali treatments a retarder is applied to the fibers from which the groups of fibers are formed.
- 15 8. The method of treating cotton fabric as recited in claim 3 wherein before the ground is subjected to the acid and alkali treatments a retarder is applied to the fibers from which the groups of fibers are formed.
- 20 9. The method of treating cotton fabric as recited in claim 4 wherein before the ground is subjected to said chemical reaction a retarder is applied to the fibers from which the groups of fibers are formed.
- 25 10. The method of treating cotton fabric as recited in claim 5 wherein before the ground is subjected to the acid and alkali treatments a retarder is applied to the fibers from which the groups of fibers are formed.

CLARENCE T. GRAHAM.

CERTIFICATE OF CORRECTION.

Patent No. 2,270,289.

January 20, 1942.

CLARENCE T. GRAHAM.

It is hereby certified that error appears in the printed specification of the above numbered patent requiring correction as follows: Page 2, second column, line 46, for "transparent" read --translucent--; page 3, second column, line 62, for "roller 18" read --roller 19--; and that the said Letters Patent should be read with this correction therein that the same may conform to the record of the case in the Patent Office.

Signed and sealed this 28th day of April, A. D. 1942.

(Seal)

Henry Van Arsdale,
Acting Commissioner of Patents.
